[57] CLAIM

The ornamental design for a combined calculator and
protective case, as shown and described.

DESCRIPTION

FIG. 1 is a top perspective view of a combined calculator and protective case showing my new design;

FIG. 2 is an inverted bottom perspective view thereof
with the latch partly open;

FIG. 3 is an inverted bottom rear perspective view of
FIG. 1;

FIG. 4 is a top rear perspective view of FIG. 1;

FIG. 5 is a top perspective view thereof in the open
position showing both top and bottom surfaces;

FIG. 6 is a left front perspective view with the cover
partly open; and

FIG. 7 is a right front perspective view with the cover
partly open.

FIG.1.

FIG.2.

FIG.3.

FIG.4.

FIG. 5.

UNITED STATES PATENT AND TRADEMARK OFFICE
CERTIFICATE OF CORRECTION

PATENT NO. :Des. 283,137

Page 1 of 3

DATED :March 25, 1986

INVENTOR(S) :Christopher J. Hamar

It is certified that error appears in the above-identified patent and that said Letters Patent is hereby corrected as shown below:

Figure 6 and 7 of the drawings should be added
as per attached sheets.

Signed and Sealed this
Fourteenth Day of October, 1986

[SEAL]
